UNITED STATES PATENT OFFICE.

PERCY BROWN AND FRANCIS JOHN BOSTOCK, OF HUDDERSFIELD, ENGLAND.

MILLING-CUTTER OR ABRASIVE-WHEEL PROFILE GENERATOR.

1,100,524.

Specification of Letters Patent. Patented June 16, 1914.

Application filed October 8, 1913. Serial No. 794,046.

To all whom it may concern:

Be it known that we, PERCY BROWN and FRANCIS JOHN BOSTOCK, subjects of King George V of Great Britain, residing at Huddersfield, in the county of York, England, have invented certain new and useful Improvements in Milling-Cutter or Abrasive-Wheel Profile Generators, of which the following is a specification.

10 The object of our invention is to provide a new or improved device for generating the profiles of milling cutters or of abrasive wheels employed in cutting and grinding worms, spirals or like gears so that whatever angle of tooth it may be desired to produce, or to grind, the device can be readily adjusted first to one angle and then to the opposite angle to generate or grind the exact profile of cutter or abrasive wheel to cut or grind the angular sides of the tooth or teeth required. Any suitable scale, such as shown at 15, is provided for indicating the angle of the cutting tool 12 with respect to the axis of the bearings 2.

25 In order that our invention may be fully understood reference is hereinafter had to the accompanying drawings, in which:

Figure 1 is an elevation of our improved milling cutter profile generator; Fig. 2 is a plan view of Fig. 1 partly in section; Fig. 3 is a sectional elevation taken on line A—A, Fig. 2, Figs. 4, 5 and 6 are elevation, plan view and sectional elevation corresponding to Figs. 1, 2 and 3 respectively, showing the device as modified in construction for use in connection with abrasive wheel profile generators, and Fig. 7 is a detail illustrating the mode of employment of the device.

Referring to the drawings, and firstly to Figs. 1, 2 and 3, the device comprises a holder 1 of suitable size and shape, having turned ends or spindles 2, 2, and a central opening 3 therethrough. The said holder is constructed to admit of its being centered and held by a chuck in a profile generating machine. Within the said opening 3 fits loosely, so as to be adapted to turn freely therein, a swiveling tool carrier 4 provided in this instance with conical headed studs or pivot pins, only one of which is shown at 5 in Fig. 2, which register with conical openings in the tool carrier. The said pins or studs rest in bearings 6 in the holder 1 and the outer ends thereof are reduced in diameter and provided with screw threads on to which take nuts 7 which when turned in

one direction slacken the parts and enable the tool carrier to be turned or swiveled about the studs 5 as a center and, when screwed up tightly in the other direction, 60 rigidly secure the tool carrier in any position to which it has been turned. Centrally of the swiveling tool carrier 4 is supported and secured by nut 8 a bush 9 which receives a spindle 10 having at one side thereof a longitudinal opening 11 into which is adapted to be inserted the profile cutter 12 which is secured in any position vertically by screws 13, or one of them, screwed through the bush 9 and abutting against the cutter 70 tool 12. By loosening the screw or screws 13 the profile cutter can be adjusted vertically to any extent within the limits of the device. The position of the profile cutter is such that the upper point of the cutting 75 edge, that is to say the point 14, is in accurate alinement with the horizontal axis of the holder 1 and with the vertical axis of the carrier 4, so that to whatever angle said carrier is moved the point 14 will be in 80 alinement or radial with the pivot center of said carrier as well as in alinement with the horizontal axis of the holder. On the carrier 4 is a scale 15 and on the holder immediately above same is a vernier (not shown). 85 Given the angle of the tooth which is to be produced by the cutter profile generator, the carrier 4 is turned on its centers until the cutter is brought to the desired angle, as ascertained from the scale and vernier, and 90 is then secured in position.

The device is held in the machine between suitable chucks 16, 16, (Fig. 7) in the usual way of holding a work spindle, and receives a rotary and an endwise motion or 95 lead for each cutting stroke, the cutting edge extending from the point 14 downward being brought into action on one side of the cutter blank 17 to cut same to the required angle said cutter blank being mounted on a 100 suitable revolving axis. When one side of the profile of the cutter has been generated, the nut 8 is released and the bush 9 partially rotated to reverse the positions of the spindle and the cutting edge of the cutter 105 110 and the carrier also is released and turned to bring the cutter to the opposite corresponding angle and then re-secured to the holder, so that the profile on the other side of the cutter blank can be generated, the profile of the milling cutter thus produced being such that when it is completed and

inserted in the milling machine it will cut the teeth in the blank to the exact angle determined by the angular position of the carrier. For generating the profile of abrasive wheels, a diamond is employed in place of a cutter and the device is therefore modified to receive the diamond and to enable the said diamond to be manually reciprocated to move to and fro along the profile of the abrasive wheel.

Referring to Figs. 4, 5 and 6 the holder 1 and swiveling carrier 4 are the same as described with reference to Figs. 1, 2 and 3. 18 represents the diamond which is secured to a spindle 19 supported in a long bearing in the bush 9 secured to the carrier 4 by nut 8. The carrier 4 is swiveled to the angle required, as previously explained, to produce the profile on one side of the abrasive wheel, and is then turned over to the opposite corresponding angle to produce the profile on the other side of the abrasive wheel, the nut 8 being released to allow of the spindle 19 being turned to the extent required to reverse the position of the diamond. A pinion 20 fast on a spindle 21, actuated by hand wheel 22, is provided in order that the operator by manually operating the said hand wheel can transmit a rotary motion first in one direction and then the other to impart, through a toothed rack on the spindle 19, a sharp reciprocating motion to the said spindle and diamond to move the latter to and fro over the profile being generated.

The means described herein comprise a simple and effective device for generating with accuracy the required profile or curved form on a milling cutter or abrasive wheel initiated from a straight line such as 14 or the diamond 18, and requires no skilled labor to obtain results with a certainty and accuracy not possible in the present methods

of generating milling cutter or abrasive wheel profiles.

The details of construction may be varied without departing from the spirit and scope of our invention as set forth in the claims annexed.

Having thus described our invention, what we claim as new and desire to secure by Letters Patent is:—

1. In a device of the character described, the combination, with a holder, of an adjustable carrier pivoted to the holder, a revoluble bush mounted in the carrier and arranged crosswise of the holder, and a cutting tool provided with a shank arranged longitudinally in the bush and eccentric of its axis.

2. In a device of the character described, the combination, with a holder, of an adjustable carrier pivoted to the holder, a revoluble bush mounted in the carrier and arranged crosswise of the holder, a cutting tool provided with a shank arranged longitudinally in the bush and eccentric of its axis, and operating mechanism for sliding the shank back and forth in the bush.

3. In a device of the character described, the combination, with a holder having spindles at its ends, of a carrier pivoted to the middle part of the holder and movable in the plane of the axis of its spindles, a revoluble bush mounted in the carrier and arranged crosswise of the holder, and a cutting tool provided with a shank arranged longitudinally in the bush and eccentric of its axis.

In testimony whereof we affix our signatures in the presence of two witnesses.

PERCY BROWN.

FRANCIS JOHN BOSTOCK.
